UNITED STATES PATENT OFFICE.

ALBERT C. SHAW, OF SAN FRANCISCO, CALIFORNIA, ASSIGNOR OF ONE-HALF TO GEORGE H. FULLER, OF SAME PLACE.

TELLURIAN.

SPECIFICATION forming part of Letters Patent No. 288,372, dated November 13, 1883.

Application filed June 23, 1882. (No model.)

To all whom it may concern:

Be it known that I, ALBERT C. SHAW, of the city and county of San Francisco, State of California, have invented an Improved Tellurian; and I hereby declare the following to be a full, clear, and exact description thereof.

My invention relates to certain improvements in tellurians; and it consists in certain details of construction as hereinafter described, 10 and specifically pointed out in the claims, as will be more fully explained by reference to the accompanying drawings, in which—

Figure 1 is a view of the apparatus. Fig. 2 is a section. Figs. 3 and 4 are details of 15 construction.

A is a standard fixed in a base, B, and having the sun-globe C supported upon the top, as will be more fully explained. This standard is turned in three sizes, diminishing toward the 20 top, and having shoulders formed, as shown. Upon the shoulder formed at the junction of the lower section with the second one is fixed a pulley, D, which is fixed to the standard.

The arm E, which extends out to support 25 the earth and carry it in its orbit around the sun, is made with a hub or sleeve, F, which is bored out to fit over the second portion of the standard, upon which it turns freely. This lower part of the arm may rest upon the pulley D, and it has flanges G formed upon each 30 side, which project downward far enough to conceal the pulley, and also protect the cord which extends from it to a corresponding pulley upon the standard supporting the earth.

Above the hub or sleeve F of this arm is the 35 large wheel H, which is bored to fit the upper and smaller portion of the standard A, resting upon the upper shoulder, where it is firmly fixed by a nut, I, which is screwed down upon it, a thread being formed upon the upper section to receive this nut. The upper part of the nut may have a smaller threaded hole made in it to receive the stem J. This stem extends upward, so that the sun-globe C may 40 be slipped down upon it, and the whole of this portion is thus simply made and easily kept in order. The arm E has a slot, K, made in the top of its outer end, as shown, with an enlarged hole at one end of the slot, through 45 which to introduce or remove the slide L, which is loose on shaft O. This slide may be

made cylindrical, as shown, and has a groove turned in it, so that it will just fit in the slot K. A screw, M, projects out through the end of the arm E, and a nut, N, upon its outer end, 55 will, when turned, move the slide L out or in, and thus tighten or relax the driving cords or belts. A spindle or stem, O, extends up through the slide L, within which it turns. Upon the lower end of this spindle is fixed a 60 pulley, P, around which the driving-cord Q passes from the pulley D of the standard A. These pulleys are of the same size; and the object of this portion of the mechanism is to retain the earth-globe R in the same relative 65 position during the revolution around the sun, and thus retain its polarity. The earth-globe is supported upon a stem, S, which is fixed at the end of a horizontal arm, T, the inner end of this arm being secured upon the top of the 70 spindle O. The angle of the stem S and the length of the arm T are so proportioned that the center of the earth-globe will be in a direct line with spindle O, and as the earth is revolved during its progress around the sun 75 the north and the south poles traverse equal circles, being equidistant from the center of motion.

Two cylindrical pieces, U U, are fixed to the spindle O just below the arm T, having 80 their ends cut at an angle, as shown, and a cam-pulley, V, turns loosely upon the spindle between the two inclined faces. This pulley is driven by a cord from the large wheel H, the proportion of the wheel to the pulley being 85 such as to give the moon the proper number of revolutions around the earth while the latter passes around the sun. The pulley V has an arm, W, projecting from one side, carrying the moon-globe X upon it, and the angle which 90 the axis of the pulley V makes with the spindle O determines the plane in which the moon revolves about the earth.

A curved arm, Y, projects from the end of the arm E, extending up over the earth-globe, 95 and a ring, Z, of wire, is fixed to this arm, encircling the earth-globe at a little distance from it and in the plane which represents the dividing-line between day and night, this construction allowing the moon to move about 100 the earth without removing the circle Z.

The base B has the usual signs of the zodiac.

marked around its periphery, and an index-arm or marker, *a*, may extend from the inner end of the arm *E*, to indicate the signs through which the earth may be passing.

5 It will be manifest that bevel-pinions may be substituted for the pulleys *D* and *P*, and a shaft having corresponding bevel-pinions may extend beneath the arm *E*, in place of the cord *Q*, to produce the desired action upon the 10 earth-globe.

In order to produce the actual effect of day and night upon the earth's surface as it revolves, to show the phases of the moon, and produce the effect of an eclipse, I form the 15 sun-globe of two hollow sections, which may be opened or separated to admit a light. The half which is toward the earth has its interior blackened, and a short adjustable tube, *b*, is fitted into an opening in this part, so as to direct the light upon the earth. The rear half of the sun-globe, or that which is away from the earth, has its interior polished, so that it will reflect and concentrate the rays of the light *f*, which is placed within the globe upon 20 a plano-convex lens, *c*, and from thence the rays pass through a lens, *d*, in the tube *B*, so as to strike upon the earth.

An arm, *e*, of elastic material—as spring 30 brass or steel—is fixed to the arm *E*, and extends up over the wheel *H*, and a point or projection in its end is made to enter the sun-globe, so as to cause it to rotate upon its axis simultaneously with the motion of the earth, and thus always keep the light upon the latter. 35 The rays of light thus falling upon the earth

and moon will produce the effect of night and day, solar and lunar eclipses, and will always show the phases of the moon.

Having thus described my invention, what I claim as new, and desire to secure by Letters Patent, is—

1. In a tellurian, the arm *E*, turning upon the central shaft, and carrying the earth-globe at the outer end, and having the slot *K*, as shown, in combination with the slide *L*, moving in said slot, the screw *M*, and the nut *N*, substantially as herein described. 45

2. The earth-globe *R*, supported and rotated upon the spindle *O*, as shown, in combination with the moon-globe *X*, stem *W*, and the pulley *V*, turning in a plane which cuts the plane of the earth's orbit at an angle, substantially as herein described. 50

3. The earth-globe *R*, supported and rotated upon the spindle *O*, and the moon-globe *X*, with its arm *W*, and driving-pulley, in combination with the curved arm *Y* and the day-and-night circle *Z*, substantially as herein described. 55

4. In a tellurian, the revolving hollow sun-globe *C*, in combination with its light *f* and polished or reflecting inner surface, the direction-tube *b*, and lenses *c d*, and the arm *e*, substantially as and for the purpose herein described. 60

In witness whereof I hereunto set my hand.
ALBERT C. SHAW.
